UNITED STATES PATENT OFFICE

MICHAEL STEIN, OF CHICAGO, ILLINOIS, ASSIGNOR, BY MESNE ASSIGNMENTS, TO CHICAGO EYE SHIELD COMPANY, OF CHICAGO, ILLINOIS, A CORPORATION OF ILLINOIS

WELDER'S HOOD

Application filed May 16, 1927. Serial No. 191,664.

This invention relates to welder's hood, and more particularly to means for permitting ready viewing of the work.

In welder's hoods it is the common practice 5 to provide a sight opening which is normally closed by a window carrying a pane or sheet of dark glass or other suitable translucent material to protect the welder's eyes from the effect of the intense light or glare during the 10 welding operation. This dark glass permits the work to be viewed in a general way during the welding operation but, necessarily, does not give a clear view of the details of the work. For this reason it has been proposed 15 to provide hingedly mounted windows for welders' hoods, this window being capable of being raised by hand to permit the welder to view the work more clearly. This arrangement is objectionable in that it necessitates 20 the use of the hand for opening the window and holding it open briefly, which is not at all times practicable. This is particularly true as regards the welder's helper who usually has 25 both hands occupied holding the work and the welding rods. It is the present practice for the welder's helper to work without a hood due to the necessity of his watching the work closely and the fact that as a general rule, both 30 of his hands are occupied. One of the main objects of my invention is to provide a welder's hood having means whereby the window can be opened and closed without necessitating the use of the hand, this hood being, therefore, adapted to be used by both the welder 35 and his assistant. A further object is to provide simple and efficient means for holding the window in raised or open position and for releasing the window to permit closing thereof, such means being also operated with- 40 out the necessity of using the hand. Another object is to provide simple means of the character stated which can be readily applied to hoods of standard construction at small cost. Further objects and advantages will appear 45 from the detail description.

In the drawings:

Fig. 1 is a front view of a welder's hood of standard construction to which my invention is applied;

Fig. 2 is a side view;

Fig. 3 is a rear view of the hood showing my invention applied thereto;

Fig. 4 is a fragmentary section, on an enlarged scale, taken substantially on line 4—4 of Fig. 3;

Figs. 5 to 8, inclusive, are fragmentary sectional views similar to Fig. 4 showing the relative positions of the various parts of the device in successive steps of opening and closing the window;

Fig. 9 is a detail of the latch member;

Fig. 10 is a detail of the releasing finger; and

Fig. 11 is a section taken substantially on line 11—11 of Fig. 6.

The hood 1 is of known construction, being usually formed of fibre or other suitable material. A head gear 2 is mounted within the hood for supporting the same upon the wearer's head with the sight opening 3 in substantial alignment with the eyes. The head gear 2 is mounted in the hood for relative turning movement to facilitate placing of the hood upon the head and its removal. The manner of constructing the hood and the head gear, 70 and of mounting the same is well known in this art and need not be described or illustrated in detail, it being understood that the hood and the associated head gear illustrated are of standard construction which are well 75 known in the welding art.

I provide a suitable rectangular frame 4 of sheet metal which is secured about the sight opening 3 in any suitable manner as by means of screws 5 and nuts 6 threaded thereon. A holding frame 7 is secured to the base flange of frame 4 in any suitable manner, as by soldering, in spaced relation to flange 8 of the frame. A sealing and cushion strip 9 of felt or other suitable material is secured between the frame 7 and flange 8 and projects beyond the same to contact with the inner face of a sheet metal window frame 10. Frame 10 is provided adjacent each corner of its upper end with a sleeve 11 which receives the end portion of a pintle rod 12 mounted through sleeves 13 at the top of frame 4. A coiled wire spring 14 is mounted about the rod 12 with one end bearing against the upper portion of hood 1, the other end of this 100

spring bearing against the outer face of window frame 10 and acting to normally hold the window closed. Frame 10 is provided with an inwardly projecting flange forming a housing 15 for reception of a pane of glass 16 disposed in rear of opening 17 through frame 10, this housing being of slightly less size than the sight opening 3. The glass pane 16 is retained in housing 15, therefore, by a resilient bowed retaining member 18 the ends of which engage beneath flanges 19 provided on housing 15 for this purpose. Obviously, any other suitable means may be employed for securing the glass in its housing. The glass 16 is very dark and substantially opaque in ordinary light so as to protect the welder's eyes from the injurious effect of the intense glare produced during welding. It is desirable, for this reason, to provide means whereby the window can be raised, when desired, to permit the welder or his helper to inspect the work closely. For this purpose I have provided means which can be readily operated by the chin for opening the window 25 as desired.

The window frame 10 is provided, at each end thereof, with an arcuate arm 20 which is rigidly secured to the frame and extends rearwardly and upwardly therefrom. A stirrup 21 is mounted within hood 1 by means of links 22 of fiber or other suitable material, the upper ends of these links being pivoted to the hood and the lower ends of the links being pivoted to the stirrup. The upper end 30 of each arm of the stirrup is pivotally connected to the upper end of the corresponding arm 20 by means of a screw 23 and a nut 24 threaded thereon, suitable spacers 25 being interposed between the arms 20 and the upper ends of the arms of the stirrup. A chin strap 26 is adjustably secured in the lower portion of the stirrup by means of headed pins 27 secured in the arms of the stirrup, these pins being adapted for cooperation with any one, 35 selectively, of a plurality of keyhole slots 28 provided in the upper end portion of each arm of the chin strap. Preferably, though not necessarily, the central portion of the chin strap is secured to the central portion of the stirrup by a screw 29 and a nut threaded thereon, or in any other suitable or preferred manner. I also preferably provide an adjustable connection between the arms of the stirrup and the arm 20 of the window frame 40. For this purpose the arms of stirrup 21 are provided at their upper end portions with a vertical series of openings 30 through any selected one of which the securing screw 23 can be passed. Chin strap 26 is also preferably provided with a front strap 27 secured thereto and disposed to pass about the front portion of the chin for holding the main chin strap 26 properly positioned, in conjunction with the links 22. When the parts are properly adjusted, the chin strap 26 is disposed

immediately beneath the wearer's chin so that by lowering the chin the window can be readily moved into open position so as to permit the work to be viewed clearly through the sight opening 3. Raising the chin permits raising of the stirrup and closing of window 10 by the spring 14.

To facilitate retaining of the window in open position I provide means controlled by the operation of the stirrup for securing the window open and for releasing it to permit closing thereof when desired. Referring more particularly to Figs. 4 to 8, inclusive, a supporting bracket 31 of substantially L-shape in plan view is rigidly secured to the front of hood 1 above the sight opening 3 and adjacent one end thereof. The outer depending arm 32 of this bracket has its lower end shaped to provide a tapered or pointed element 33 which extends into a conical recess in the upper end of a bearing ferrule 34 provided at its upper end with an outer annular shoulder 35. An expansion coil spring 36 is mounted about the body portion of ferrule 34, at its upper end, the lower end portion of this spring being mounted about a similar ferrule 37 which receives a pointed or tapered element 38 projecting upwardly from the lower portion 39^a of a latch member 39 which is rockably and slidably mounted upon the arm 31. This member is provided with an arcuate slot 40 through which passes a screw 41, this screw passing through an opening in the arm 31, and a nut 42 being threaded upon the inner end of the screw. The hook portion 39^b of the latch member 39 is disposed at an angle to the lower portion 39^a, the bill 41' being extended in substantial parallelism with portion 39^b to provide a slot 42' for reception of a detent 43 extending inwardly 45 from the adjacent arm 20 substantially at right angles thereto. Movement of the member 39 about the pin or screw 41 is limited by a pin 44 secured in portion 39^b adjacent the upper end thereof, this pin projecting through a rectangular opening 45 which extends through the arm 31. A trip or release finger 46 is pivoted on the screw 41 at the outer face of member 39. This finger is provided at its lower end with a slot 47 which receives a pin 48 secured to member 39 below slot 40 and projecting from the outer face of this member. When the latch member 39 is in inoperative position (Fig. 8) the finger 46 projects forwardly beyond arm 20 in position to be struck by a trip pin 48' carried by arm 20. This serves to return the latch member to operative position for engagement with detent 43 when the stirrup is again operated for opening the window.

The operation of the latch mechanism will be clearly understood by reference to Figs. 5 to 8, inclusive. In Fig. 5 the parts are shown in their normal positions, i. e., the positions which they occupy when the window

is closed. Upon downward movement of the stirrup for opening the window, the window is raised and as it approaches its uppermost position the detent 43 contacts with the inner 5 rounded edge of the hook portion of latch member 39 rocking this member about the screw 41 and moving it into the position illustrated in Fig. 6. The detent then passes beyond the end of the hook bill 41' so as to 10 permit the detent to enter the slot 42'. At this time the spring 36, which is not moved beyond center position, acts to swing the latch member about the screw 41 so as to cause the hook portion to move toward the detent and upon release of the stirrup the detent 43 enters slot 42' and causes the latch member to be moved upwardly and inwardly about screw 41 due to movement of 15 arm 20 caused by slight downward movement 20 of the window upon release of the stirrup. This swings the lower portion of latch member inwardly so as to dispose the spring 36 with its lower end inwardly beyond center as I have illustrated. This upward and inward movement of the latch member with the 25 detent is limited by contact of pin 44 with the top edge of the opening 45. This movement of the latch member also serves to swing the releasing finger 46 outwardly and forwardly into the position illustrated in Fig. 30 7. The detent and the latch member serve to hold the window in open position until the stirrup is again depressed. Upon the succeeding downward movement of the stirrup the detent is moved downwardly out of slot 42 and the spring 36, being beyond center as above stated, acts to swing the member 39 about the screw 41, the lower end of this member moving inwardly and the upper end 35 moving outwardly, movement of the latch member being limited by contact of the pin 44 with the forward wall of opening 45 adjacent the upper end thereof. This serves to move the hook 41' outwardly or forwardly 40 beyond the path of movement of the detent 43 and also serves to rock the finger 46 into its full outer position. Upon release of the stirrup the window is moved downwardly 45 into closed position, raising the stirrup and causing the tripping pin 48 to contact with the outer end of finger 46 so as to swing the upper end of this finger upwardly and inwardly about the screw 41. The relative 50 positions of the parts immediately prior to complete closing of the window is illustrated in Fig. 8. This movement of the finger 46 serves to swing the lower end of latch member 39 outwardly or forwardly of the hood so that the lower end of the spring 36 is moved 55 past center in a forward direction as the window approaches closed position, this spring then acting to return the latch member to its operative position illustrated in Fig. 5. It will thus be seen that I have 60 provided simple and highly efficient means whereby the window may be opened and held in open position upon operation of the stirrup, the window being released and permitted to close upon a succeeding operation or depression of the stirrup, the latch member 70 being held out of the path of movement of the detent upon the return upward travel of the stirrup and all parts being returned to their normal operative positions.

While I have illustrated the lower portion 75 39^a of the latch member 39 as cut out to provide an opening or frame within which the spring 36 is disposed, this particular arrangement is not essential as it will be obvious that the tapered members 38 and 38^a 80 can be secured to the arm 31 and portion 39^a, respectively, and offset therefrom. As above indicated, and as will be understood, changes in construction and arrangement of parts of the invention may be resorted to without departing from the field and scope of the same, and I intend to include all such variations, as fall within the scope of the appended claims, in this application in which the preferred form only of my invention is 85 disclosed.

What I claim is:—

1. In combination, a hood having a sight opening, a window hingedly mounted at its upper edge adjacent the upper edge of the 90 opening for closing the same, arms extending rearwardly and upwardly from said window, a stirrup connected at its ends to the arms, a detent carried by one of the arms, a latch member disposed for engagement with the 95 detent and cooperating therewith to hold the window raised upon operation of the stirrup, means for yieldingly urging the latch member into operative position and for moving it into inoperative position upon subsequent 100 operation of the stirrup, and means for causing said member to be returned to operative position by said yielding means as the window is returned to closed position.

2. In combination, a hood having a sight 105 opening, a window normally closing said opening and hingedly mounted adjacent the top thereof, yielding means urging the window in closing direction, arms extending upwardly and rearwardly from the window, a 110 stirrup connected at its ends to the upper ends of the arms, a supporting bracket adjacent one end of the sight opening, a latch member slidably and rockably mounted on the bracket, means limiting rocking and sliding movement of the latch member in either direction, yielding means for completing the throw of the latch member beyond center in either direction, a detent on one of the arms 115 cooperating with the latch member for holding the window open when the stirrup is operated, the detent acting upon release of the stirrup to move the latch member beyond center in releasing direction, said latch member 120 being thrown beyond center upon the suc- 125 130

ceeding operation of the stirrup, and means for moving the latch member beyond center in holding direction as the window is lowered into closed position.

5. In holding and releasing latch means, a supporting bracket, a latch member rockably and slidably mounted on the bracket, means limiting rocking and sliding movement of the latch member in either direction, 10 yielding means for completing the throw of the latch member in either direction beyond center, and a trip finger mounted on the bracket and connected to the latch member for moving it beyond center in one direction 15 when said trip finger is actuated by a co-operating member.

4. In combination, a hood having a sight opening, a window movable into and out of position to close said opening, latch and 20 detent means for positively holding the window open, and chin operated means for opening the window and for releasing it from said holding means for closing the window.

5. In combination, a hood having a sight 25 opening, a window movable into and out of position to close said opening, an operating arm secured to the window, latch and detent means coacting with the arm for positively holding the window open, and a chin operated member connected to the arm, said holding means being released by movement of the arm in window opening direction succeeding opening of the window.

In witness whereof, I hereunto subscribe 35 my name this 9th day of May, 1927.

MICHAEL STEIN.
